United States Patent Office.

FRANCIS ERNEST THOMAS, OF NEW YORK, N. Y., ASSIGNOR TO FELLOWS,
HOFFMAN & CO., OF SAME PLACE.

Design No. 4,851, dated April 25, 1871.

DESIGN FOR GAS-FITTINGS.

The Schedule referred to in these Letters Patent and making part of the same.

To all whom it may concern:

Be it known that I, FRANCIS ERNEST THOMAS, of New York city, in the county and State of New York, have invented a new and original Design for Gas-Fittings; and I do hereby declare that the following is a full, clear, and exact description thereof, which will enable others skilled in the art to make and use the same, reference being had to the accompanying drawing forming part of this specification.

This invention relates to a new design of gas-fittings or joints, and consists more particularly in a new ornamental shield applied to the "barrels" and "cock-handles" of the fittings, and in a new design for the portions of joint adjoining the barrels, and for the elbows.

These designs are applicable for all gas-fittings of the nature shown in the drawing, in which—

Figure 1 shows an L-pendent cock;

Figure 2, a swivel-pendent cock;

Figure 3, a bracket-cock;

Figure 4, a middle swing;

Figure 5, a universal swing;

Figure 6, a two-light pendent cock; and

Figure 7, a side nipple.

The ornamental shields *a* on the barrels *b b* of the several fittings shown are oval, and have within them rhomboidal leaves or rosettes, *c c*.

Similar shields, *a*, with ornaments *c c*, are shown on the handles of the cocks *f f*.

The pipes *d*, near the barrels *b* and the elbows *e e*, have their circumferences grooved, parallel to their axes, as shown in all the figures, except in fig. 7, where the side nipple has but one ornamental barrel.

I claim as my invention—

1. The ornamental shields *a* applied to the barrels *b* and handles *f* of gas-fittings, as set forth.
2. The grooved pipes *d* and elbows *e*, combined with the ornamental barrels *b* of gas-fittings, as set forth.

FRANCIS ERNEST THOMAS.
